R. E. REARDON.
DUMMY PRACTICE RIFLE.
APPLICATION FILED MAR. 12, 1917.

1,382,120.

Patented June 21, 1921.

UNITED STATES PATENT OFFICE.

ROBERT E. REARDON, OF OTTAWA, ONTARIO, CANADA.

DUMMY PRACTICE-RIFLE.

1,382,120.

Specification of Letters Patent. Patented June 21, 1921.

Application filed March 12, 1917. Serial No. 154,302.

To all whom it may concern:

Be it known that I, ROBERT EDWIN REARDON, a subject of the King of Great Britain, residing in the city of Ottawa, in the Province of Ontario, Dominion of Canada, have invented a new and useful Improvement in Dummy Practice-Rifles, of which the following is a specification.

My present invention relates to improvements in dummy practice guns designed for practice in shooting at miniature targets and preferably with dummy cartridges.

One object of the invention is to provide a dummy practice rifle or gun complete in itself as an article of manufacture and having incorporated therein as a unitary part thereof a projectable rod capable of co-acting with a miniature target, which rod will be projected a material distance by the firing act, and will be instantly returned or retracted into the barrel.

Another object is to provide a dummy gun which may be manufactured at minimum cost and by the use of which the user may become an expert marksman at no expense for ammunition.

A further object is to provide a gun of this character capable of all the practice use of a regulation gun, but which will be provided with means for preventing the accidental use of a live cartridge, and a still further object is to provide improved means for marking the target to indicate the point struck.

With these and other objects in view the invention includes the novel features of construction and arrangement and combination of parts hereinafter described, my said invention being defined by the appended claims.

An embodiment of my invention is illustrated in the accompanying drawings in which:

Figure 1, is a partial vertical longitudinal section through my improved dummy gun.

Fig. 2, is a plan view partially broken away and with parts omitted.

Fig. 3 is a section on line 3-3 of Fig. 1.

Fig. 4 is a detail view and,

Figs. 5 and 6 are detail views of modifications.

It will be understood that my dummy rifle is intended to be used with a miniature target, preferably of strip form, carrying two bull's eyes, one for sighting and the other for receiving the impact of the projectable rod.

Referring by reference characters to this drawing the numeral 11 designates the main portion of the dummy gun which includes the stock 12, the fore stock 13, barrel cover 60 14, and barrel 15.

Within the barrel and forming a permanently connected part thereof is a projectable rod 28 which is designed to be projected for a material distance to strike the target and to be instantly retracted within the barrel in position for a second firing. As it is desirable to form the barrel of some material other than metal, I prefer to line the bore 17 thereof with a metal tube indicated at 18 which may have its rear end threaded as at 19 to engage corresponding threads in a cast iron breech section A, this breech section being inserted in the opening 22 in the stock part 11 from the top. This stock part 75 11 may be made of any suitable economical material such as molded plastic composition, as also may the stock 12, and these are preferably modeled after the army rifle as closely as possible.

The tube may be further secured in position by means such as a set screw 26 threaded through the under side of the barrel and having a pointed end engaging an indentation or recess in the wall of the tube.

The rod 28 has its forward end slidably held in a central bore or passage in a plug 27 held permanently in the bore of the gun, conveniently by an annular groove in the plug engaged by an annular rib in the bore 90 lining and this rod has at its inner end an enlarged head 30 against which bears one end of a long and relatively weak spiral spring 29 which encircles the rod and bears against the plug or block 27 at the opposite 95 end.

The spring is of just sufficient tension to draw the rod back into the bore after it has been projected, but permits it to be projected by a blow upon its rear end, the length and 100 weakness of the spring permitting the major portion of the rod to be projected.

The front end of the rod is adapted to have a plurality of tips of different character detachably and interchangeably connected thereto, and a convenient means of effecting such connection is to thread its outer end to engage correspondingly screw threaded sockets in the tips as clearly shown in Figs. 1 and 5.

In order to project the rod 28 it must be struck by a blow sufficient to overcome the

tension of spring 29 and the means by which I accomplish this comprises a plunger 41 propelled by a spring 49 of a strength sufficient to give a blow which will project rod 5 28 against the tension of spring 29. I prefer to use in my dummy gun, dummy cartridges such as shown at 51, each comprising a member having an exterior of cartridge shape, and having in place of the usual primer a 10 sliding rod or plunger 52 extending completely through a central longitudinal opening in the cartridge and having one end adapted to contact with the head 30 of rod 28 and the other end to receive the impact of 15 plunger 41. A portion of the central opening is enlarged to receive a spring 53 which encircles the rod 52 and bears at one end against the annular shoulder formed by said enlargement and at its other end against an 20 annular shoulder or enlargement on the rod thereby holding said rod normally retracted. To manipulate the cartridges I may provide a slidable breech bolt 39 having a suitable operating handle 40 and which breech 25 bolt serves as a container for the spring 49. The breech bolt has an ejector 45 at its forward end for engaging the rim of the cartridge and withdrawing and ejecting it in the usual manner. The spring 49 encircles 30 a rod 48 forming a reduced extension of the plunger, and bears at one end on the plunger and at the other end against the end wall 50 of the breech bolt. The plunger has a shoulder 47 designed, when retracted, to engage 35 a locking projection on the trigger piece 37 which is pressed into engaging position by spring 38, the usual trigger guard being shown at 36.

When it is desired to use the gun as a repeating rifle and supposing it to be in readiness for firing with the parts in the position shown in Fig. 1 the breech bolt is drawn back by the handle 40 which withdraws and ejects the cartridge, and simultaneously a 40 fresh cartridge is forced into position by the supporting plate 60 pressed upward by lever 57 under the action of spring 58. As the breech bolt is drawn back the plunger moves back with it until the shoulder 47 is 45 engaged by the trigger. The shoving forward of the breech bolt forces the fresh cartridge into firing position and compresses the spring 49 due to the fact that the plunger is held against forward movement by 50 the trigger. The pulling of the trigger then releases the plunger which is drawn forward by the spring and through rod 52 delivers a blow to rod 28 sufficient to project the latter from the bore of the gun as heretofore 55 explained.

In order that the gun may be operated without moving the cartridges I provide the rod 48 of the breech bolt with a cocking

handle 42 at its rear end by which the plunger may be drawn back and the spring compressed without moving the breech bolt. 65

If it is desired to use the gun for single shots only, no cartridges are inserted in the magazine, and a cartridge with cut away rim which the extractor 45 cannot engage 70 is placed in the chamber to maintain connection between firing plunger and rod.

To prevent the firing of a live cartridge, should one be placed in the gun, the head of the plunger is made of such shape as to 75 be ineffective on the cartridge primer.

As hereinbefore stated the rod 28 is designed to carry a removable tip, enabling various kinds to be used. In Fig. 1 I have shown a tip having a barb on which may 80 be applied a rubber head when a pricking point is not desired.

This tip may be removed and tip 65 substituted, having a split portion to hold a pencil lead 66. 85

In Fig. 6 I have shown means for making an ink mark on the target which comprises a tip 67 having a seat face or hammer like head 69 adapted to be inked by an ink pad 60 pivoted at 70. A claw member 71 acted 90 upon by spring 70 tends to normally throw the pad down out of the path of the tip, but pressure of the tip on the claw when the plunger is retracted throws the pad up against the receiving face. 95

Having thus described my invention what I claim is:

1. As an article of manufacture a dummy gun having a member extensible from the barrel thereof and spring means holding 100 said member normally retracted.
2. As an article of manufacture a dummy gun having a member extensible from the barrel thereof, spring means holding said member normally retracted and spring hammer means actuatable to give forward movement to said member. 105

3. As an article of manufacture a dummy gun having a limitedly extensible target striking rod, a spring hammer and a dummy 110 cartridge for transmitting the blow of said spring hammer to said rod.

4. As an article of manufacture a dummy gun having a target striking member actuatable by a dummy cartridge. 115

5. A device of the class described including dummy cartridge firing mechanism, said mechanism including means for preventing the firing of a live cartridge.

6. In combination with a target practice 120 rod, printing means carried on the rod, means for inking the printing means and means for automatically removing and replacing the inking means in inking position upon extension and retraction of the rod. 125

R. E. REARDON.
